UNITED STATES PATENT OFFICE.

EMIL G. H. STEIN AND JOHN MANDEL, OF NEW YORK, N. Y.

MACHINE FOR BENDING SHEET METAL.

SPECIFICATION forming part of Letters Patent No. 762,500, dated June 14, 1904.

Application filed June 16, 1903. Serial No. 161,700. (No model.)

To all whom it may concern:

Be it known that we, EMIL G. H. STEIN and JOHN MANDEL, citizens of the United States, residing at New York, in the county of New York and State of New York, have invented certain new and useful Improvements in Machines for Bending Sheet Metal, of which the following is a specification, such as will enable those skilled in the art to which it applies to make and use the same.

The object of this invention is to provide a well-known form of sheet-metal-bending machine with improvements whereby sheet metal may be conveniently bent into pipe-sections angular in cross-section and adapted for use as air-conduits, ventilating-pipes, flues, &c., and provided with interlocking end pieces or couplings, such as is shown and described in United States Letters Patent granted to us on the 21st day of April, 1903, No. 726,004.

The machine to which our improvements are applied is that covered by Letters Patent of the United States, granted to George C. Keene July 1, 1884, No. 301,128, and the said improvements will be fully described in the following specification in connection with the said machine of such parts thereof as may be necessary to fully illustrate and describe our improvements.

The invention is fully disclosed in the following specification, of which the accompanying drawings form a part, in which the separate parts are designated by suitable reference characters in each of the views, and in which—

Figure 1 is a front view of a machine of the class referred to provided with our improvements; Fig. 2, a sectional end view thereof; Fig. 3, a sectional front view of the end thereof shown in Fig. 2; Fig. 4, a view of a detail of the construction which we employ; Fig. 5, a front view of a part of the upper movable jaw of the machine as improved by us; Fig. 6, a bottom plan view thereof; Fig. 7, a front view of a part of the lower movable jaw of the machine; Fig. 8, a plan view thereof; Fig. 9 a plan view of the swinging jaw of the machine; Fig. 10, a front view thereof; Fig. 11,

an inner perspective view of an attachment which we apply to the upper movable jaw of the machine; Fig. 12, a perspective plan view of an attachment which we apply to the lower jaw of the machine; Fig. 13, an inside perspective view of an attachment which we apply to the swinging jaw of the machine; Fig. 14, a view similar to Fig. 11, showing a modification; Fig. 15, a view similar to Fig. 12, showing a modification; Fig. 16, a view similar to Fig. 13, showing a modification; Fig. 17, a view of a die or dies which we employ, and Fig. 18 a perspective view of another detail of the construction.

In the drawings forming part of this specification we have shown the machine covered by United States Letters Patent No. 301,128, dated July 1, 1884, hereinbefore referred to, or such parts thereof as are necessary to illustrate our improvements, and this machine is provided with a lower movable jaw *a*, an upper movable jaw *b*, and a front swinging jaw *c*, having a handle or handles *c*, by which it is operated. All of these jaws are mounted in the top portion of a rigid main frame, of which the upright end members *d* form the principal parts, and the lower jaw *a* is adapted to be raised by means of pedals *d*, mounted on the shaft *d* in the bottom of the frame and provided with heads *d*, through which the shaft *d* passes and which are provided with recesses *d*, which receive the lower ends of vertically arranged and movable members *d*, which operate in sockets *d* in the lower part of the jaw *a*.

The swinging jaw *c* is supported in front of the bottom jaw *a* by means of trunnions *c*, which pass through the frame members *d* and are provided with collars *c*, to which are rigidly secured arms *c*, provided with weights *c*, which assist in the manipulation of said jaw.

The upper and vertically-movable jaw *b* is provided at each end with a projection *b*, and these projections fit in and are vertically movable in corresponding recesses in the end frame members *d*, and over said projections are placed screws *b*, which limit the vertical movement of said jaw. The means for raising this

jaw constitute one of the features of our invention and consist of journals b^4 , mounted in the end frame members d , and each of which is provided at its inner end with a cam-block b^5 and at its outer end with a sleeve b^6 , to each of which are secured a handle b^7 and a rod b^8 , provided with a weight b^9 , and these weights assist in raising the jaw b , the cam-blocks b^5 being adapted to bear on the bottom surface of said jaw, as clearly shown in Figs. 2 and 3. One side of the outer end of the journals b^4 is cut away, and the sleeves b^6 are similarly formed, so that said sleeves cannot turn on said journals, and the handles b^7 and rods b^8 are rigidly connected with said sleeves.

The front part of the jaw a is provided with a top flat surface a^2 and a sharp front edge a^3 , and the jaw b is provided with a sharp front edge b^1 and with a flat bottom surface b^2 , which 20 preferably consists of a hard steel plate secured thereto in any desired manner. In the practice of our invention we secure to the forwardly-directed edge of the upper jaw b a supplemental attachment f , which is V-shaped in 25 cross-section, and to the top flat surface of the jaw a we secure a plate g , and to the front portion of the swinging jaw c we secure a plate h . One form of the attachment f and plates g and h is shown in Figs. 14 to 16, inclusive, 30 and another form thereof is shown in Figs. 11 to 13, inclusive. In using the forms shown in Figs. 14 to 16, inclusive, they may be secured in position by means of screws, and for this purpose the said attachment f and plates 35 g and h are provided, respectively, with holes f^2 , g^2 , and h^2 , and in order that the plate h may be held with sufficient rigidity it is provided with a rib h^3 , which fits in a corresponding groove in the swinging jaw c , and in order 40 to further adapt the device to our purpose the front edge of the plate g is beveled, as shown at g^3 , and the top edge of the plate h is provided with a thickened member h^4 , the back of which is beveled, as shown at h^5 , to correspond 45 with the bevel of the plate g . Although these attachments may be secured to the jaws a , b , and c by screws or in any other way, we prefer to connect them with said jaws in the following manner: In the top surface of the jaw 50 a we form transverse grooves a^4 of the tongue-and-groove class, and the plate g is provided with corresponding tongues g^4 , as shown in Fig. 12. The bottom surface of the jaw b , at the edge thereof, is also provided with grooves b^4 of the tongue-and-groove class, and the attachment f is provided with corresponding 55 tongues f^4 , as shown in Fig. 11, adapted to enter said grooves, and in order to place the attachments f and g in position they are simply moved backwardly, so that the tongues g^4 and f^4 on the plate g and attachment f will enter the corresponding grooves a^4 and b^4 in the jaws a and b . The swinging jaw c is also provided in the top thereof with diagonally-

arranged and transverse grooves j , (clearly shown in Fig. 9,) and the plate h is provided beneath the thickened top portion h^4 thereof with corresponding tongues or projections j^2 , and in practice the plate h is moved laterally to the left and backwardly, so as to cause the 70 tongues or projections j^2 to enter the grooves j , while the rib portion h^3 enters the corresponding groove j^3 in the swinging jaw c . The swinging jaw c may also be preferably provided at one or both ends with a pivot-clip 75 d , which is adapted to be turned so as to overlap the ends of the plate h and assist in holding it in position, as shown in Fig. 4.

In United States Letters Patent No. 728,004, granted April 21, 1903, and hereinbefore referred to, we have described and claimed a form of pipe used as an air-conduit, ventilating-pipe, and the like, said pipe consisting of separate sections angular in cross-section and connected at the ends by angular projections 85 and locking devices adapted to be slipped onto said projections, the connection of the separate sections of the pipe being such that the interior surface thereof is flush, smooth, and even throughout, the separate pipe-sections 90 being adapted to be connected by simply applying the locking device and disconnected by removing said locking device, and it is for the purpose of forming the angular projections on the ends of the pipe-sections and for forming 95 said sections that this improvement.

It will be understood, of course, that a sheet of metal in order to be formed into a pipe-section which is angular in cross-section must be bent into a plurality of sides, preferably three 100 or four, and in order to do this the angular interlocking projections at the ends of the pipe-section, as shown and described in our prior patent, above referred to, must first be formed before the sheet of metal is bent into 105 the form of a pipe-section, and in order to do this the end of the sheet is slotted at regular intervals corresponding with the width of the sides of the pipe-section, and the interlocking projections are formed by placing the end of 110 the sheet between the jaws a and b of the machine, raising the jaw a , so as to clamp the sheet between the jaws a and b , and then swinging the jaw c forwardly and upwardly and bending the sheet up over the sharp edge of the jaw b . After 115 this is done the sheet may be taken out and one of the side edges thereof inserted between the jaws a and b and the above-described operation repeated, and in this way the pipe-section is formed. In order, however, to form 120 the pipe-section after the interlocking end projections have been formed on the sheet, a space must be provided for said interlocking projections between the jaws a and b , and it is for this purpose that the attachments consisting of the parts f , g , and h are employed. These attachments may be of any desired 125 length, and one or more of them may be em-

ployed, and in Fig. 1 of the drawings two of said attachments are shown, separated by the line *k*, and it will be understood that in bending a sheet of metal into a pipe-section the interlocking end projections thereof are inserted between the jaws *a* and *b* at the ends of the attachments, while the body of the sheet is clamped between said attachments. A similar result may be accomplished to an extent by cutting out the upper surfaces of the bottom jaw *a*, at the ends thereof, as shown at *m* in Fig. 3, and in using this form of construction the interlocking end projections of the pipe-sections are first formed, as hereinbefore described, and in bending a sheet of metal into a pipe-section the interlocking end projections are passed into the transverse slot or opening *m* at one end of the jaw *a*, while the sheet is clamped between the jaws *a* and *b* and bent to form the pipe-section, as hereinbefore described. The swinging jaw *c* is provided with curved end arms *m*², by which it is supported and on which the journals *c*⁶ are formed, and these end arms, as the machine is shown in Fig. 1, conceal the cut-out portions or recesses *m* at the ends of the jaw *a*; but it will be understood that said jaw *a* is similarly formed at both ends, and the top jaw *b* is provided at each end of the bottom bearing-surface thereof with similar recesses *m*³ for a similar purpose. It will also be understood that whenever desired the attachments comprising the parts *f*, the plate *g*, and the plate *h* may be removed and the machine used, as originally intended, for bending sheet metal for the purpose of forming cornices and other articles, and in this event we provide dies of the form shown at *n* and *n*² in Fig. 17 to close the grooves or recesses *a*⁴ and *i* in the jaws *a* and *b*, respectively, and in order to close the recesses *j* in the jaw *c* we provide a plate *o*, (shown in Fig. 18,) which is similar in all respects to the plate *h*, except that the thickened top portion *h*⁴ is removed, and this plate *o* is connected with the jaws *c* in the same manner as the plate *h*.

The length of the attachments *f*, *g*, and *h* will depend on the character of the work to be done, and, if desired, they may extend approximately the full length of the jaws; but in this event the attachments *g* and *h* will be cut off at one end, so as to form a transverse space to accommodate the interlocking end projections of the pipe-sections when the sheet of metal is being bent to form the pipe-section.

As thus constructed, it will be seen that the attachments *f*, *g*, and *h* do not change the form of the front clamping edges of the jaws *a* and *b* nor of the swinging jaw *c*, but simply provide means whereby said clamping surfaces and edges may be made shorter or longer, as desired, the thickness of the attachments

f and *g* or the adjacent portions thereof being such as to afford open spaces between the main bodies of the jaws into which the interlocking end projections of the pipe-section are passed in the operation of bending a sheet of metal to form the pipe-section. It will also be observed that the attachments which we connect, if desired, with the upper and lower movable jaws of the machine and with the swinging jaw are detachable and may be applied whenever necessary, and the machine when these attachments are not in position may be used for all the purposes for which it was originally intended, and that said attachments constitute supplemental jaw devices, which may be applied to the machine for the purpose herein specified whenever necessary.

Having fully described our invention, what we claim as new, and desire to secure by Letters Patent, is—

1. A sheet-metal-bending machine, provided with vertically-movable top and bottom clamping-jaws the adjacent surfaces of which are provided at the front thereof with projecting edges, and a swinging jaw mounted in front of the bottom clamping-jaw, each of said jaws being provided with detachable attachments which form supplemental clamping-surfaces and which also form at the ends thereof spaces between the clamping-jaws when the latter are in operation, substantially as shown and described. 85

2. A machine for bending sheet metal, provided with vertically-movable clamping-jaws arranged one above another, a supplemental swinging jaw supported in front of the bottom clamping-jaw, said clamping-jaws being provided at their adjacent surfaces with forwardly-directed edges, and each of said jaws being provided with detachable attachments forming operating edges and whereby the clamping-surfaces of the clamping-jaws are separated, substantially as shown and described. 100

3. A machine for bending sheet metal, provided with vertically-movable clamping-jaws arranged one above another, a supplemental swinging jaw supported in front of the bottom clamping-jaw, said clamping-jaws being provided at their adjacent surfaces with forwardly-directed edges, and each of said jaws being provided with detachable attachments whereby the clamping-surfaces of the clamping-jaws are separated, the clamping-surface of the bottom clamping-jaw being also cut out transversely at the ends thereof, substantially as shown and described. 110

4. A machine of the class described provided with vertically-movable clamping-jaws arranged one above another and means for moving the upper jaw vertically comprising journals mounted in the ends of the frame of the 125

machine, cam-blocks connected with the inner ends of said journals and adapted to bear on said jaw, means for turning said journals so as to raise said jaw, and set-screws for limiting the upward movement of said jaw, substantially as shown and described.

In testimony that we claim the foregoing as our invention we have signed our names, in

presence of the subscribing witnesses, this 12th day of June, 1903.

EMIL G. H. STEIN.
JOHN MANDEL.
